UNITED STATES PATENT OFFICE.

BRUNO RICHTER, OF NEW YORK, N. Y.

NECKSCARF.

SPECIFICATION forming part of Letters Patent No. 245,866, dated August 16, 1881.

Application filed May 21, 1881. (No model.)

To all whom it may concern:

Be it known that I, BRUNO RICHTER, a citizen of the United States, residing at New York, in the county and State of New York, have invented new and useful Improvements in Scarfs, of which the following is a specification.

This invention consists of a scarf provided with a shield and means to attach it in position, and with a flap attached along the scarf-front at or near a longitudinal central portion thereof, said flap being capable of turning or swinging on its point of attachment from one portion of the scarf-front to another, for changing the appearance of the same.

In the upper part of the reversible flap is secured a strip of soft sheet metal or other equivalent flexible and non-elastic material, so that, when the flap is reversed, by slightly bending the flexible strip, the upper edge of the reversing-flap can be brought to lie flat upon the part below.

This invention is illustrated in the accompanying drawings, in which Figure 1 represents a face view of my scarf when the reversible flap is turned to the right. Fig. 2 is a transverse section in the plane x x , Fig. 1. Fig. 3 is a face view when the reversible flap is turned to the left. Fig. 4 is a section of the reversible flap in the plane y y , Fig. 5. Fig. 5 is a face view of the upper part of the reversible flap, partly in section.

Similar letters indicate corresponding parts.

In the drawings, the letter A designates the front of my scarf, and B is the neck-band, both the front and the neck-band being connected to the shield C in the usual way.

D is the reversible flap, which corresponds in shape to one-half of the front, and is secured at its inner edge, a, to the center-line of said front, so that it can be turned down either to the right or to the left, the position to the right being shown in full lines in Fig. 2, and the position to the left in dotted lines.

In the upper part of the reversible flap is secured a strip, b, of soft sheet metal or other equivalent flexible and non-elastic material, said strip being placed in an oblique position, as shown in Fig. 5, and extending into the upper corner, c, of the reversible flap. By bending this metallic strip slightly in one or in the other direction, the upper corner, c, of the reversible flap is caused to lie snugly upon

the parts below, and said corner is readily retained by the shirt-collar or by the vest.

By means of my reversible flap a double scarf is obtained. For instance, if the right-hand half of the front is covered with black silk and the left-hand half with blue silk, and if the reversible flap is covered with black silk on the right-hand side and with blue silk on the left-hand side, the front of the scarf looks blue if the reversible flap is turned to the right, as shown in Fig. 1, and a black front is produced by turning the reversible flap to the left, as shown in Fig. 3. If the entire front is covered with one color and both sides of the reversible flap with the same color, the scarf can be worn until one side is soiled and by reversing the flap a new and clean front is obtained.

The neckband may also be covered with different colors—for instance, with black on one side and blue on the other—and it can easily be attached to the shield, so that it can be reversed and its exposed face be made to correspond in color to the front.

What I claim as new, and desire to secure by Letters Patent, is—

1. The combination, with a scarf-front provided with a neckband for attaching it in place, of a flap having one edge attached at or near a central longitudinal portion of said scarf-front, and adapted to turn on its point of attachment from one portion of the scarf-front to another for changing the appearance of the same, substantially as described.

2. A scarf-front provided with a shield and means to attach it in position, and with a flap having one edge attached at or near a central longitudinal portion of the scarf-front, and adapted to turn on its point of attachment from one portion of the scarf-front to another for changing the appearance of the same, substantially as described.

3. The combination, with the reversible flap D and scarf-front A, of a strip, b, of a flexible and non-elastic material secured in the flap, substantially as and for the purpose set forth.

In testimony whereof I have hereunto set my hand and seal in the presence of two subscribing witnesses.

BRUNO RICHTER. [L. s.]
